See application file for complete search history.

FIG. 1 is a perspective view of the tire cavity protector, showing my new design;

FIG. 2 is a left side perspective view showing my design in an alternate position;

FIG. 3 is a left side perspective view thereof;

FIG. 4 is a side elevation view thereof;

FIG. 5 is a top view thereof; and,

FIG. 6 is a bottom view thereof.

The broken line showing of a tire is included for the purpose of illustrating portions of the “article” and forms no part of the claimed design.
